United States Patent Office.

J. P. BENOIT, OF DETROIT, MICHIGAN.

Letters Patent No. 96,076, dated October 26, 1869.

IMPROVEMENT IN PITCHING BARRELS.

The Schedule referred to in these Letters Patent and making part of the same.

To all whom it may concern:

Be it known that I, J. P. BENOIT, of Detroit, in the county of Wayne, and State of Michigan, have invented a new and useful Improvement in Pitching Barrels; and I do hereby declare that the following is a full, clear, and exact description thereof, which will enable those skilled in the art to make and use the same, reference being had to the accompanying drawings, forming part of this specification.

The invention relates to an improvement upon the means usually employed to pitch barrels and analogous articles, and consists in the combination of a series of pipes and valves, whereby the cool current of air from the blower may be diverted from the fire and turned upon the pitched barrel or other article, for the purpose of cooling the same.

In the accompanying sheet of drawings—

Figure 1 represents a side elevation of the furnace partly in section, as through the line *z z* of fig. 2.

Figure 2 is a horizontal section looking from the line *y y* of fig. 1.

Similar letters of reference indicate corresponding parts.

A is the furnace, which is cylindrical in form, mounted in an upright position on a frame, *B*, which is supported on wheels *C*, so that the furnace may be readily transported from place to place.

D is the ash-pit of the furnace, which is also an air-chamber for receiving a current of air from a blower of any suitable description.

E is the pipe which conveys the air from the blower into the chamber, the same being connected with the blower, or with a pipe from the blower by means of the flange *F*.

G and *H* are valves, by which the current of air from the blower is changed from the air-chamber *D*, into a discharge-pipe attached to the pipe *I*.

This change is made when it is desired to force cold air into the barrel for cooling the pitch.

The grate *J* is placed a short distance above the chamber *D*.

The heated gases and gaseous products of combustion are forced from the furnace by the current of air from the blower through the grate and fuel, and into the tubes *K*. One or more of these tubes may be used.

L represents discharge-pipes, which are slipped on to the tubes *K*, from which the air is conducted to the barrel to be pitched. By the heated air and gases thus introduced, the barrel becomes heated to such a degree that the pores of the wood are opened and the pitch is melted or rendered so liquid by the heat that it readily enters and fills the pores, the barrel being rolled or agitated, so that the liquid pitch is brought in contact with the entire inner surface of the barrel. When this is accomplished, and a sufficient quantity of pitch adheres to the surface, cold air may be introduced from the cold-air pipe *I*, to expedite the cooling.

M represents the cover for the aperture in the top of the furnace, through which the fuel is introduced, and will act as a safety-valve on the furnace. This method is applicable to barrels, casks, and kegs, of every description, for the purpose described.

In the above description, I have detailed the various parts of an apparatus to which my improvement is preferably attached, but merely for the purpose of more perfectly exhibiting the operation of the pipe-arrangement.

I am aware that the furnace is, in all essential respects, without patentable novelty; but

What I do esteem as of my invention, and desire to protect by Letters Patent, is—

As an attachment to a pitching-furnace, a system of pipes, *E F I*, and valves *G H*, arranged with respect thereto, in the manner shown and described, and for the purpose specified.

J. P. BENOIT.
